US00D635114S

(12) **United States Design Patent**
Asabu et al.

(10) **Patent No.:** US D635,114 S
(45) **Date of Patent:** ** Mar. 29, 2011

(54) **PORTABLE TERMINAL**

(75) Inventors: **Hiroko Asabu**, Daito (JP); **Koji Horimoto**, Daito (JP)

(73) Assignee: **Kyocera Corporation**, Kyoto (JP)

(**) Term: **14 Years**

(21) Appl. No.: **29/363,534**

(22) Filed: **Jun. 10, 2010**

(30) **Foreign Application Priority Data**

Apr. 5, 2010 (JP) D2010-008498

(51) **LOC (9) Cl.** **14-03**

(52) **U.S. Cl.** ..... **D14/138 AB**

(58) **Field of Classification Search** ..... D14/138 AB,
D14/496, 341, 345, 346, 203.3, 203.4, 203.7,
